FOR MAKING BRICKS AND SIMILAR ARTICLES.

UNITED STATES PATENT OFFICE.

JULIUS FREDERICK MOORE POLLOCK, OF LEEDS, GREAT BRITAIN.

IMPROVEMENT IN BRICK-MACHINES.

Specification forming part of Letters Patent No. 116,484, dated June 27, 1871.

To all whom it may concern:

Be it known that I, JULIUS FREDERICK MOORE POLLOCK, of Leeds, in the county of York, Kingdom of Great Britain and Ireland, engineer, have invented a new and useful Improved Machine for Making Bricks and similar articles; and I do hereby declare the following to be a full, clear, and exact description of the same, reference being had to the accompanying drawing and to the figures and letters marked thereon.

According to this invention the crushing-rolls, pug-mill, molds, and pressing-dies, with their actuating mechanism, are all arranged in combination upon one base-plate, and the material to be worked is fed through a hopper to the crushing-rolls, passing from them into the pug-mill, wherein it is tempered, and which forces it into the molds, wherein it is formed (when making bricks) into perfect, common, or unpressed bricks of the ordinary well-known descriptions; and these unpressed bricks are afterward conveyed, by self-acting means, from the molds to the pressing-dies, which latter are made slightly larger laterally than the former, and wherein the bricks are finally pressed and condensed (to prepare them for drying or baking) between top and bottom plates combined with cross-heads and side rods, according to the specification of my former patent, No. 94,337, dated 31st August, 1869, preferring however, for greater convenience, to reverse the position of the cylinder shown in the drawing of said specification.

The crushing-rolls are actuated by worm-wheels and worms or endless screws running in vessels containing oil or other lubricant, and the pug-mill is provided with an adjustable trap-door or opening at its lower end, which serves as a vent in case of an excessive downward pressure of the clay and for other useful purposes. And in order that others skilled in the art may be enabled to make and use my invention, I annex a drawing thereof, in which—

Figure 1, Sheet 1, is a sectional elevation of a machine constructed according to my invention, but without platform; Fig. 2, Sheet 2, an elevation at right angles to the foregoing; Fig. 3, Sheet 3, a sectional plan through the line A B of Figs. 1, 2, and 5; Fig. 4, Sheet 4, a detached section (through C D, Figs. 1 and 2) of the ratchet motion, by which intermittent motion is given to the mold-table; Fig. 5, a detached elevation of the steam-press; and Fig. 6, a plan of the press-cylinder.

a a are a pair of crushing-rollers, and *a' a'* fixed scrapers to prevent the clay from clinging to them. *b* is an ordinary pug-mill provided with a hopper, *b¹*, for catching all that falls from the rollers, and having a sliding or adjustable door, *b²*. *c* is the pug-mill shaft, provided with knives *d* and a double-bladed bottom-knife, *d'*. *e* is the table, turning on a fixed stud, *e**, and bearing upon an anti-friction roller, *y*, placed under that part of the table which is beneath the pug-mill. *e¹ e¹* are the molds in the table; *e² e²*, their bottom plates; *e³ e³*, their stocks or guide-rods; and *e⁴ e⁴*, the anti-friction rollers, which raise the rods by passing up an incline, *e⁵*, (seen best in Fig. 1,) and move the plates and molded bricks from the position shown at X to that at Y. *f* is the bottom disk, in which are sockets *i³* to guide the mold-plates *e²*; and *g*, the ring from which it receives motion by means of the pawl *h¹*; *h*, a spring, which presses the pawl *h* into the recesses of the ratchet-disk *f*; and *h²*, my improved eccentric or cam arrangement for drawing the pawl *h* back and holding it out of gear, so that the other parts of the machine may be worked without turning the table. Reciprocating motion (in this case through about a quarter of a revolution) is given to the ring *g* by means of the connecting-rod *g¹*, whose other end is actuated by the pin of the rotating crank or disk *g²* affixed to the shaft *o*. A second pawl may prevent any return motion of the table. *i* is the cylinder of the press, by which the molded bricks are pressed, and *i¹* its piston and piston-rod, which I prefer to cast in one piece. The piston-rod is rigidly connected with two cross-heads, *j j¹*, and side rods *j²*. *k* is the die in which the bricks are pressed between cross-head *j¹* and a loose block, *t⁶*, sliding in said die; and *l l l* are the rollers for driving the delivery-belt or band *m*, which passes also over a small roller, *n*, for bringing it close to the press-die. *n* is the valve-rod, actuated intermittently from the shaft *o* by means of the cam *p* and lever *p¹*, whose fulcrum is carried by a bracket at the point *b²*, as will be readily understood from the drawing. The lever *p¹* is slotted, and in its slot it carries an adjustable spindle provided with an anti-friction roller, which takes into the groove in the cam *p*, but may be drawn back out of the influence of the cam by unscrewing a nut and sliding the spindle along the slot in the lever. The nut is, by preference, made in the form of a small hand-wheel, as shown at *p³*. *r* is the delivering-lever, by

which the molded bricks are delivered from the rotating molding-table *e* to the press-die *k*. This lever, whose fulcrum is at *r*¹, is actuated by a second cam, *r*², on the shaft *o*, and gives a reciprocating motion to a slide, *r*³, faced with felt or other woolen material, and working on a fixed slide-bar, *r*⁴. The lever *r* also gives motion, through a connecting-rod, *s*, to the check or guard-lever, *t*, having its fulcrum at *t*¹. The molds *e*¹ are lubricated in succession by the padded plunger *u*, which is attached to and reciprocates with the rod *u*¹, working in the fixed guide *u*², and actuated by the disk *u*³ and connecting-rod *u*⁴, as shown best in Fig. 2. In combination with this arrangement for lubricating the sides and bottoms of the molds, and from them the corresponding parts of the bricks, I employ a lubricating roller, *v*, carried by an arm, *v*¹, hinged at *v*². This roller lubricates the upper sides of the molded bricks as they pass under it on their way to the press. *w* is a tank or vessel formed in the cast-iron framing of the machine, and contains oil or other lubricant, which may be supplied to the plunger *u* and roller *v* by means of pipes provided with regulating-taps or cocks. I prefer to use a pipe having two branches with taps or cocks for supplying lubricant to the plunger, but for the roller I have found that one orifice is sufficient. To further guard against adhesion of the brick to the top plate of press, I heat the latter by passing steam through it. *1* is the driving-pulley, by which motion is imparted to the machine. *5* is a pinion keyed to one end of the shaft *3*, and giving motion to the wheel *6* keyed onto the shaft *7*. This shaft *7* also carries the spur-wheels *8* and *9* and the miter-wheel *10*. The spur-wheel *8* gives motion to another spur-wheel, *11*, turning on a fixed stud. This wheel *11* gives motion to the vertical shaft *o* through the medium of the miter-wheels *12* and *13*. The wheel *9* gives motion to the wheel *14* for actuating the disk *u*³. The miter-wheel *10* gives motion to the miter-wheel *15*, which is keyed upon the shaft *c* of the pug-mill. The driving-shaft *c* also carries two worms, one of which is shown in section at *16* in Fig. 2. These worms run in vessels containing oil or other lubricant, as shown in section at *17* in Fig. 2. The worms impart motion in opposite directions to two worm-wheels, one of which is keyed to the shaft of each crushing-roller, as shown at *18* in Fig. 2. The shaft *o* carries a spur-wheel, *19*, which drives the delivery-rollers *l* through the medium of the spur and miter-wheels *20*, as is shown in plan at Fig. 3. The shaft of one of the delivery-rollers *l* carries a band-wheel, *21*, from which motion is imparted to the band-wheel *22*, secured to the axis of the cylindrical brush *23*, as shown in Figs. 1 and 3. In the arrangement I have drawn, the motive power of the press is obtained from steam entering the valve-chest *i*² by the pipes *24* and exhausting through the pipe *25*; but I do not confine myself to the use of presses worked by steam. *Q* is the base-plate, upon which the whole of the mechanical parts are arranged to operate in combinations, *z z* being the main pillars and framing of the machine, as is clearly illustrated in the draw-

ing. *z'* is an ordinary platform for the attendant, which is partly shown only in Fig. 1.

The operation is as follows: The clay or brick-earth is thrown into the hopper *H* above the rollers *a a*; by passing between them it is crushed, and it then enters the pug-mill *b*, falling by its own gravity until it comes under the influence of the helical knives *dd*. These knives *d d* rotate, and so cause the clay or brick-earth to descend, and while it is descending the said knives mix and amalgamate it, and water is admitted through perforations in the pipe *P* (the supply of which may be regulated by the attendant) for the purpose of rendering the clay or brick-earth plastic. The descent of the clay continues until it is forced by the double-bottom knife *d'* into a compact mass into the mold *X*. When this mold is full the table *e* rotates, by means of the intermittent motion it receives from the disk *f* and ratchet *h*, before referred to; the brick is then passed under the lubricating-roller *v*, by which its top is lubricated; it is then raised by the incline *e*⁵ to the position shown at *Y*, in Figs. 1 and 3, and from this position it is removed, by the delivering-lever *r* and its slide *r*³, to the press. Steam is then admitted above the piston *i*¹ and gives the pressing blow, after which the steam is admitted below the piston, and raising the latter, the cross-head *j*¹, and the block *t*⁶, which, as it rises, carries the brick out of the die *k*. The pressed brick is finally pushed forward onto the delivery-belt or band *m* by the advance of the next molded brick, and is carried to any convenient distance from the machine, ready for drying or baking. The molds *e* in the table, from which the bricks have been taken, afterward successively assume the position in which the lubricating-plunger *u* enters them, and oils their sides and bottom plates previously to their again passing under the pug-mill, as hereinbefore described; after which the molds are refilled from the pug-mill for making other bricks, and the operation proceeds as before. In starting the machine the ratchet motion of the table is thrown out of gear and the vent-door of the pug-mill opened wide; the machine is then put in motion, with the table standing still, until a stream of compact clay issues from the pug-mill vent *b*²; the vent is then nearly closed and the table thrown into gear. By these means the first brick is produced perfect without leaving any mess or loose dirt about the working parts of the machine. The machine is capable of making either pressed or unpressed bricks, at the will of the attendant.

Having described the nature of my invention and the manner of performing it, I would remark that the details shown in the drawing may be modified without departing from the distinctive features of my invention: thus, for instance, it will be evident that the molds and dies may be arranged in sets of two or more, so as to produce several bricks simultaneously.

What I claim as of my invention, and desire to have secured to me by Letters Patent, is—

1. The combination in a brick-machine, of a pug-mill, molds *e* receiving the clay from said mill, and each provided with a plunger, *e*², a slide,

r^3 , a lubricating-roller, v , and a lubricating-plunger, n , the whole operating substantially as and for the purpose described.

2. The combination of the series of molds e , the slide r^3 , and the press, to which the molded bricks are conducted by the action of the slide, substantially as described.

3. The combination of the movable table having molds e , and a supplementary lubricating-plunger n supplied with lubricant, and operated substantially as described.

4. The combination, with the table, its molds e and plungers e^2 , of the lubricating-roller v , arranged to pass over the surface of the bricks while in the molds, substantially as set forth.

5. The combination of the plunger of the press and a lower cross-head operating with the plunger and with a block, t^6 , in the die k , to raise the bricks from the die, as set forth.

6. The delivery-slide and lever r , in combination with the check or guard lever t for determin-

ing the exact position of the brick to be pressed, substantially as described.

7. The combination, with the delivery-rollers l and belt m , of the rotating cylindrical brush 23 for removing excrescences from the bricks as they leave the machine, substantially as described.

8. The arrangement of the circular table e and lower disk f , having sockets v^8 for guiding the stems of the mold-plate e^2 , as specified.

9. The combination of the table e , disk f , ring g , its pawl, and devices for operating the said ring intermittently, as described.

In testimony whereof I have signed my name to this specification in the presence of two subscribing witnesses.

JULIUS F. M. POLLOCK.
